UNITED STATES PATENT OFFICE.

MARCUS SOBEL, OF SAN FRANCISCO, CALIFORNIA.

BEDPOST FOR BRASS OR IRON BEDS.

1,079,523.

Specification of Letters Patent.

Patented Nov. 25, 1913.

Application filed November 23, 1912. Serial No. 733,164.

To all whom it may concern:

Be it known that I, MARCUS SOBEL, a citizen of the United States, residing at San Francisco, in the county of San Francisco and State of California, have invented certain new and useful Improvements in Bedposts for Brass or Iron Beds; and I do hereby declare the following to be a full, clear, and exact description of the invention, such as will enable others skilled in the art to which it appertains to make and use the same.

This invention relates to corner bedstead locks, and has as an object to provide a simple means secured to the bed post, whereby the side and end bars of the ordinary frame bed may be securely locked.

Another object of the invention is to provide means for bracing the supports of the side end bars against lateral displacement.

With these and other objects in view the invention comprises certain novel constructions, combinations, and arrangements of parts as will be hereinafter more fully described and claimed.

In the drawings:—Figure 1 represents one bed post with my invention applied thereto shown in top plan. Fig. 2 is a fragmentary view showing my invention in top plan in detail. Fig. 3 is a side elevation of the interior of my corner lock, the side bar being shown in section. Fig. 4 is a side elevation of the side bar locking means. Fig. 5 is a detail view showing one end of the side bar.

Like reference characters designate corresponding parts throughout the several views.

Generally, this invention aims to provide a bracket having an end wall, a side wall, and an offset portion formed between the walls, the offset portion being provided with means for securing the same to the bed post. The end wall is associated with the end bar of the bedstead in such a way as to project across the offset piece and form a reinforcement, extending from one side of the offset piece to the side wall. There is also provided a brace secured to the end wall and end bar extending to the side wall of the bracket, this brace serving to strengthen the bracket.

In the drawings 1 designates the usual hollow bed post in which is located a rounded strip 2 through which pass suitable bolts 3. The bolts 3 are designed to pass through

the offset portion 4 of the bracket 5, the offset portion of the bracket being rounded slightly to conform with the surface of the post 1. By means of the bolts 3 and the rounded strip 2 the curved portion of the offset part 4 is made to fit closely against the post 1 and is held against lateral movement.

The extending end wall 5 of the bracket is designed to engage an end bar 6 forming part of the end of the bed. From Fig. 2 it will be seen that the end bar 6 is provided with a slit 7 formed in the under web thereof, and that part of the bracket 5 is designed to pass through this slit 7. That part of the end bar 6 which extends between the slit 7 and the side walls 8 is designed to bridge the offset piece 4 and thereby brace the side wall 8. By reference to Figs. 3 and 4 it will be seen that the upper end of the offset piece 4 is extended as at 9, this extending end projecting above the tops of the end and side walls.

By reference to Fig. 4 it will be seen that the side wall 8 is provided with a pocket 10 formed integral therewith, the pocket 10 preferably being stamped from the wall 8 and having its two sides convergent. The brace 11 secured at one end of the end bar 6 by suitable bolts 12 has the other end thereof secured to the side wall 8 by means of suitable bolts 13, the latter end of the brace 11 being substantially at right angles to the plane of the end wall, so that a rigid support is provided between the end and the side walls. The side bar 14 is provided with a projecting lug 15 which may be formed integral therewith or riveted as may be desired. The sides of the projecting lug 15 are also convergent so that as the lug is projected within the pocket 10, the same will lock securely.

When it is desired to assemble a bed provided with corner posts as described, it is merely necessary to slip the projecting lugs 15 within the pockets 10 and let the same slide into a locking position. It will be seen from Fig. 4 that the end of the side bar 14 falls just below the level of the projecting end 9 of the offset portion 4 of the bracket, so that as the bar 14 is lowered the end will fit snugly against said projecting end and act with the lug 15 to provide a secure lock. A further brace is obtained from the construction of the end bar 6 for the project-

ing end 9 engages the upper web of the end bar 6, which engagement together with the bolts 12 serve to lock the end bar rigidly to the bracket.

5. What I claim is:—

1. In a corner lock for bedsteads, a bed post, an end bar having a slit cut therein, a bracket held to the post, and having an end wall passing through the slit in the side bar, 10 a side wall formed on the bracket, a side bar held to the side wall, and means for holding the end bar to the end wall of the bracket.

2. In a corner lock for bedsteads, a bed 15 post, a bracket associated therewith, the bracket having an end wall, a side wall, and an offset portion formed between the said walls, the offset portion being secured to the bed post, an end bar associated with the end 20 wall of the bracket, the end bar having a slit therethrough, and adapted to receive the end wall of the bracket, and a side bar held to the side wall of the bracket.

3. In a corner lock for bedsteads, a bed 25 post, a bracket associated therewith having end and side walls, the bracket being provided with an offset portion intermediate the walls, an end bar secured to the end wall and having a slit therein through which the 30 end wall of the bracket passes, the extending end of the end bar bridging the offset portion, and a side bar held to the side wall.

4. In a corner lock for bedsteads, a bed 35 post, a bracket associated therewith, the bracket having an end wall, a side wall extending from the bracket at right angles to the end wall, and an offset portion between the walls, an end bar, a brace, means passing through the end bar and one end of the 40 brace for securing the same to the end wall of the bracket, means associated with the side wall for securing the other end of the brace thereto, a side bar associated with the side wall, and means for securing the bracket 45 to the bed post.

5. In a corner lock for bedsteads, a bed 50 post, a bracket having side and end walls at right angles to each other and an offset portion extending between the walls, an end bar having a slit therein through which the side wall passes, the extending end of the end bar bridging the offset portion, and engaging the side walls, a brace, one end of

which is secured to the end wall, means passing through the brace for securing the 55 said bar to the side wall, and a side bar associated with the side wall.

6. In a corner lock for bedsteads, a bed post, an end bar associated therewith, a bracket secured to the bed post, said bracket 60 having a side wall, a brace secured to the side wall and end bar, the side wall having formed integral therewith a pocket, a side bar, and a lug projecting therefrom and engaging the pocket.

7. In a corner lock for bedsteads, a bed post, a bracket associated therewith and having a side wall, a pocket formed in the side wall, the bracket having an offset portion extending from the side wall and substantially at right angles thereto, the offset portion having the upper end thereof extending above the side wall, a side bar, one end of which engages the extending end of the offset portion, and a lug formed on the 75 side bar and engaging the pocket.

8. In a corner lock for bedsteads, a bed post, a bracket secured to the bed post, having end and side walls, an offset portion extending between said walls, an end bar secured to the end wall and having a slit therein, the end wall passing through the slit, a projecting end extending from the offset portion and above the end wall, the end bar being adapted to engage said extending end, and a side bar secured to the side wall.

9. In a bed construction, an end bar, a bracket secured to the end bar and provided with an offset portion, said portion 90 passing through the end bar and braced thereby, and a bed post secured to the offset portion of the bracket.

10. In a corner lock for bedsteads, a bed post, an end bar, a bracket secured thereto, 95 the bracket bowing outwardly to provide an offset adapted to engage the bed post, a side bar secured to the bracket and means for bracing the bracket.

In testimony whereof I affix my signature in presence of two witnesses.

MARCUS SOBEL.
